C. C. TOMKINSON

LOCKING MECHANISM FOR DOORS

Filed July 23, 1921

Inventor
Charles C. Tomkinson
By his Attorney
E. M. Marshall

UNITED STATES PATENT OFFICE.

CHARLES C. TOMKINSON, OF PLAINFIELD, NEW JERSEY, ASSIGNOR TO JOHN EDWARD OGDEN, OF MOUNTAINVILLE, NEW YORK.

LOCKING MECHANISM FOR DOORS.

Application filed July 23, 1921. Serial No. 486,975.

To all whom it may concern:

Be it known that I, CHARLES C. TOMKINSON, a citizen of the United States, and a resident of Plainfield, county of Union, and 5 State of New Jersey, have invented certain new and useful Improvements in Locking Mechanism for Doors, of which the following is a specification.

This invention relates to doors and more 10 particularly to latching or locking mechanism for doors.

The invention hereinafter described has been particularly worked out for use in connection with large doors of the sectional type 15 such as are used for closing large openings in pier sheds, warehouses and like structures. Doors of this character are subjected to severe wind pressure and to other severe stresses and strains and therefore must be 20 so constructed and mounted as to withstand such unusual stresses.

One of the objects of this invention is to provide a sectional door having means for stiffening or strengthening the door against 25 wind pressure.

Another object of the invention is to provide door latching mechanism that will be positive and "snappy" in its action.

Another object of the invention is to provide 30 means for automatically releasing door latching mechanism upon the raising of the door sections to open the door.

Another object of the invention is to provide latching mechanism for doors that will 35 firmly hold the door in closed position and a construction that is positive in its action and may be readily unlatched.

Another object of the invention is to provide 40 a lock, which is released by the opening movement of the door and reset for snapping action, by the continued opening movement as the section breaks away from the jamb.

Another object of the invention is to provide 45 a construction of latching mechanism which is simple in construction and may be economically manufactured and further to provide means for adjusting the latch for its most efficient operation.

50 Further objects will appear from the following specification.

In the embodiments of the invention illustrated the above objects are attained by a 55 latch preferably pivoted and resiliently actuated and adapted to engage the upper door

section when this section is in its closed position and to firmly retain the section against the lintel or jamb of the door opening. Releasing means in the form of a strip, preferably resilient, is carried by the lower door 60 section and is adapted to engage and release the latch when the lower section has been raised to a position in which it overlies the upper section and before the sections are swung inwardly or away from the vertical. 65

Referring to the drawings;

Fig. 1 is a sectional elevation of a portion of a sectional door provided with a latch constructed in accordance with my invention. 70

Fig. 2 is a view similar to Fig. 1, which shows the relation of the parts when on the closing movement, the two sections have returned to the jamb and before any downward movement of lower door section has 75 occurred.

Fig. 3 is a top plan view of the construction shown in Figs. 1 and 2, and

Fig. 4 is a sectional elevation of another embodiment of the invention. 80

In the drawings the upper portion of the upper door section is shown at 10 and the upper portion of the lower section is shown at 11 and the lower section is provided with a flange 12 which slides in an overlapping 85 flange 13 carried by the upper section. The wall of the building structure is shown at 14 and a channel iron 15 forms a lintel or header of the door opening.

For a more complete showing of the door 90 sections and the operating mechanism, attention is directed to Patent No. 1,282,113 Ogden et al., October 22, 1918. It will be understood without further showing or description that the door section 11 is raised 95 vertically to a position in which it overlies the upper section 10 whereupon these sections will be swung laterally, inwardly, in unison, to an inclined or horizontal position.

The latching mechanism therefore must be 100 so constructed that it will retain the door in closed position and against wind pressure but will release the door when the sections are to be swung inwardly to their fully opened position and furthermore will be in 105 latching position upon the return of the sections.

Referring to Figs. 1-3 inclusive, I have shown a latch comprising a member 16 pivoted on a pin 17 carried by bracket 18 se- 110

cured to the wall 14. The member 16 has formed thereon or secured thereto an upwardly extending lug 19 and a flat spring 20 is secured to the bracket 18 and engages the lug thereby forcing the pivoted member downwardly. The member 16 at the other side of its pivot has also formed thereon a lug 21 which is screw-threaded and receives a threaded adjusting screw or bolt 22. The 10 inner end of the screw 22 is adapted to engage a flange 23 formed on the bracket 18 and a lock nut 24 retains the member 22 in adjusted position. By turning the member 22 the member 16 will be swung on its pivot and the normal position of the member 16 will be varied, to adapt it to variations in structure.

The latch member 16 is offset as shown at 25 and intermediate its end and the offset portion is inclined as shown at 26, the extreme end portion being substantially flat or horizontal as shown at 27. The upper door section 10 has secured thereto an upwardly extending bracket or keeper 28 adapted to be engaged by the offset portion 25 of the latch 16.

In order to release the latch the lower section 11 has secured to its top a strip or tripper 29, resilient and offset at its upper end, as shown at 29'.

The operation of the construction shown in Figs. 1, 2 and 3 may be described briefly as follows: Assuming that the upper section is in closed position as shown in Fig. 1, the latch 16 will engage the bracket 28 and firmly hold this section against the lintel 15. When, however, the door is opened and the lower section 11 is raised the strip 29 will engage the end 27 of the latch and will raise the latch to the dotted line position (Fig. 1) whereupon the door sections may be swung laterally inwardly to inclined or horizontal position. As the door sections swing inwardly, tripper 29 is withdrawn from latch 16, which by the action of the spring 20, drops into a position determined by the adjustment of the screw 22 and is then ready to engage keeper 28 on the return movement of the door. After the engagement, the 50 position of the parts is as shown in Fig. 2. Thus the latch is unhindered in its return movement to latching position by the releasing strip and the operation is snappy and quick due to the absence of any friction or engagement between the latch and releasing strip.

In Fig. 4 a modified form of latching mechanism is illustrated and in this construction the latch is carried by a bracket 30 secured to one of the side posts or to the side wall 14 of the door opening. In this construction a latch 31 is pivoted at 32 to the bracket and a pair of adjustable stops 33 and 34 similar to the stop 22 limit the 60 upper and lower movement of the latch

about the pivot. The stop 33 prevents an overthrow of the latch as the door is slammed against the jamb. A spring 35 engages a lug 36 on the latch and presses the latch downwardly.

The upper door section 10 has an opening 37 therein through which the latch 31 is adapted to extend and a slotted bracket 38 is secured to the section and forms an abutment for the latch. As in the other structure the latch 31 has an offset portion 39 adapted to engage the bracket 38 and has also an inclined portion 41 adjacent its end. At its extreme end and on the upper side the latch has a portion 42 inclined to the vertical for a reason hereinafter set forth.

The lower door section 11 is slidably mounted on the upper section and is provided with an opening 43 through which projects the end 44 of a resilient strip 45 secured as shown at 46 to the section 11. In the form of the invention shown in Fig. 4 the portion 44 of the strip 45 is disposed substantially at right angles to the main portion of this strip.

The construction shown in Fig. 4 operates as follows. When the upper door section is in closed position, it will be firmly locked against the lintel 15 of the door by the latch 31 but when the lower section is raised the end 44 of the resilient strip 45 will engage the portion 41 of the latch and will raise the latch to its upper limit of movement determined by the stop 33 thereby releasing the door sections for their lateral or inward movement. When the sections are swung laterally the upper section 10 will move away from the latch and the latch will move through the opening 37. Upon the return of the door sections from their open position the latch will enter the opening 37 and the end 44 of the strip 45 will engage the portion 42 of the latch thereby assisting in returning the latch to its locking position. As the section 11 moves downwardly the strip 45 will spring laterally thereby passing over the end of the latch.

Although certain specific embodiments of the invention have been particularly illustrated and described, it will be understood that the invention is capable of further modification and that changes in the construction and in the arrangement of the co-operating parts may be made without departing from the spirit or scope of the invention as expressed in the following claims.

What I claim is:-

1. A door comprising a plurality of vertically and laterally movable sections, a latch for locking the upper section in closed position, and means carried by a lower section for releasing the latch upon the opening movement of the said lower section said releasing means and latch being so relatively constructed and arranged that the latch will

snap into closed position on the upper section when said section is closed and said releasing means will clear the latch as said latch is closed and upon return movement 5 of said lower section.

2. A door comprising a plurality of vertically and laterally movable sections, a latch for locking the upper section in closed position, adjacent stops for limiting the 10 movement of said latch, and means carried by a lower section for releasing the latch upon the opening movement of the said lower section said releasing means and latch being so relatively constructed and arranged 15 that the latch will snap into closed position on the upper section when said section is closed and said releasing means will clear the latch as said latch is closed and upon return movement of said lower section.

20 3. A door comprising a plurality of vertically and laterally movable sections, a latch for locking the upper section in closed position, and resilient means carried by a lower section for releasing the latch upon 25 the opening movement of the said lower section and adapted to engage a portion of the upper surface of and to spring over the latch upon the return movement of the said lower section.

29 4. A door comprising a plurality of vertically and laterally movable sections, a latch for the upper section, said section having an opening through which the latch is adapted 35 to project when the door is closed and means carried by a lower section and adapted to engage and release the latch when the door is opened.

39 5. A door comprising a plurality of vertically and laterally movable sections, a pivoted latch for the upper section, said section having an opening through which the latch is adapted to project when the door is closed and means carried by a lower section and adapted to engage and release the 45 latch when the door is opened.

6. A door comprising a plurality of vertically and laterally movable sections, a pivoted, resiliently actuated latch for the upper section, said section having an opening through which the latch is adapted to project when the door is closed and means carried by a lower section and adapted to engage and release the latch when the door is opened.

55 7. A door comprising a plurality of vertically and laterally movable sections, a latch for the upper section, said section having an opening through which the latch is adapted to project when the door is closed and resilient means carried by a lower section and adapted to engage and release the latch when the door is opened.

8. A door comprising a plurality of vertically and laterally movable sections, a latch 65 for the upper section, said section having an

opening through which the latch is adapted to project when the door is closed, means carried by a lower section and adapted to engage and release the latch when the door is opened, and adapted to engage and move 70 the latch to locking position when the said lower section is closed.

9. A door comprising a plurality of vertically and laterally movable sections, a latch for the upper section, said section having an 75 opening through which the latch is adapted to project when the door is closed, means for limiting the opening and closing movement of said latch and means carried by a lower section and adapted to engage and release the latch when the door is opened.

10. A door comprising a plurality of sections arranged to overlap one another and swing inwardly and upwardly, a pivoted latch adapted to lock the upper section in 85 closed position, means carried by a lower section adapted to release the latch, means for returning the latch to locking position after the sections have been swung inwardly, and adjustable means for limiting the return 90 movement of the latch.

11. A door comprising a plurality of sections arranged to overlap one another and swing inwardly and upwardly, a pivoted, resiliently closed, latch adapted to lock the 95 upper section in closed position, means carried by a lower section adapted to release the latch, said means supplementing the resilient latch closing means in snapping the latch to locking position after the sections 100 have been swung inwardly.

12. A door comprising a plurality of sections arranged to overlap one another and swing inwardly and upwardly, a pivoted latch adapted to lock the upper section in 105 closed position and resilient means carried by a lower section and having an offset end portion adapted to engage and release the latch as the lower section is raised, said end portion only engaging the latch after said latch has been closed upon the return movement of the lower section.

13. A door comprising a plurality of sections arranged to overlap one another and swing inwardly and upwardly, a pivoted 115 latch adapted to lock the upper section in closed position and resilient means carried by a lower section and having an offset end portion only adapted to overlap the end of the latch and adapted to engage and release 120 the latch as the lower section is raised.

14. A door comprising a plurality of sections arranged to overlap one another and swing inwardly and upwardly, a pivoted latch adapted to lock the upper section in 125 closed position and a single piece, resilient member carried by a lower section and having an offset end portion adapted to engage and release the latch as the lower section is raised.

15. A door comprising a plurality of vertically and laterally movable sections, a latch for locking the upper section in closed position, and means carried by a lower section for releasing the latch upon the opening movement of the said lower section, said releasing means comprising an upright portion disposed in a plane spaced from a ver-

tical plane passing through the free end of the latch and having an offset end portion adapted to overlap the end of the latch.

In witness whereof, I have hereunto set my hand this 19th day of July, 1921.

CHARLES C. TOMKINSON.

Witness:

I. B. MOORE.
